RICHARD B. CHILLAS, JR., OF CLEVELAND, OHIO, ASSIGNOR TO NATIONAL CARBON CO., OF CLEVELAND, OHIO, A CORPORATION OF NEW JERSEY.

STEADYING DEVICE FOR VERTICAL ARC-LAMPS.

1,184,824.

Specification of Letters Patent.

Patented May 30, 1916.

Application filed January 22, 1912. Serial No. 872,698.

To all whom it may concern:

Be it known that I, RICHARD B. CHILLAS, Jr., a resident of Cleveland, in the county of Cuyahoga, in the State of Ohio, have invented new and useful Improvements in Steadying Devices for Vertical Arc-Lamps, of which the following is a clear and exact description.

My invention is an improvement in 10 steadyng-devices for vertical arc lamps, and is intended to be used with flaming arc lamps of the vertical type in which there is only one conductor connected to the lower carbon holder.

15 The object of my invention is to arrange the lamp conductors so that the arc will not have a tendency to remain at one side.

Another object is to construct a lamp that will burn the electrodes so that they will 20 always have substantially square or uniformly rounded ends.

Another object is to cause the electrodes to be consumed in such a way that the slag deposited thereon will have a less tendency 25 to put the lamp out.

Another object of my invention is to construct a lamp that will burn evenly and steadily, and that will have fewer outages than the usual type of vertical flaming carbons now in use.

Another object is to neutralize the magnetic forces in the vicinity of the arc.

Further objects will appear in the appended description particular reference being 35 had to the drawings in which:

Figure 1 is one type of invention for accomplishing the desired results. Fig. 2 is a slightly different modification. Fig. 3 is still another modification. Fig. 4 shows 40 the electrode points frequently obtained when used in prior lamps. Fig. 5 shows the electrode points commonly obtained from trims of prior lamps with deposits of slag material preventing them from touching. Fig. 6 shows the electrode points resulting 45 from the use of my improvement on the lamps. Fig. 7 represents the electrodes burned in my improved lamps having deposits of slag material which do not prevent 50 the carbons from touching.

The upper electrode 1 and the lower electrode 2 are connected together by a flexible connection 3 passing over the pulley 4. The connection 3 is fastened to, but insulated from, a conducting support 5 which

is directly fastened to the lower electrode 2. The connection is fastened to the upper electrode 1 by means of the insulating member 6. The lever arm 7 is connected to the wheel 4 through the clutch 8 and is connected at its other end to the core 9 of the solenoid 10 in the lamp circuit. 60

One of the lamp terminals 11 is connected to the upper electrode 1, while the other terminal 12 is connected to the solenoid 10. 65 The support 5 is connected by means of a flexible conductor 14 to a semi-circular ring 18. At the extremities of this member two oppositely placed conductors 19 and 20 lead downward past the arc and are joined below 70 the arc at a point 21. By means of a conductor 22 the point 21 is connected to the remaining terminal of the solenoid 10. The current enters at connection 11, flows through the upper electrode 1, through the arc, lower 75 electrode 2, support 5, and connection 14 to the semi-circular ring or connection 18, the current dividing and going to opposite sides of the upper conductor, and then going downward through the connection 19, 20 80 to the point 21. Here the currents unite again, flowing out through terminal 12. The support 5 and conductor 22 should be on opposite sides of the arc, and at an equal distance therefrom. The conductors 19 and 85 20 should also be on opposite sides of the arc, and at equal distances therefrom. The diagrammatic representation is intended to represent the plane of the conductors 19 and 20 as being at substantially right angles 90 to the plane of the conductors 5 and 22. However, this is not essential. Since the conductors in each of these planes balance each other independently of the conductors in the other plane, it is not necessary for 95 the two planes to be placed at any particular angle. It might be troublesome to place the conductors 19 and 20 equidistant from the arc and so I have shown resistances 23, 24 so that the currents in these two conductors 100 can be properly adjusted to compensate for the unequal spacing. It will be understood that a very slight change or adjustment of the resistance will be sufficient and the adjustment can be properly made by lengthening or shortening the wires 19 and 20 without using any other resistance. I have, however, shown adjustable resistances in order to make clear to the eye that the current can be balanced by adjustment of 105 110

the resistances in circuit. In this modification it is clear that the current in support 5 will balance the current in conductor 22, while the current in conductor 19 will balance the current in conductor 20, and this balance will be maintained even if the arc moves up or down through a distance of two or three inches, so that the arc will be free to position itself throughout the life of the carbons.

Since there is no tendency to keep the arc to one side of the lamps the electrodes burn with blunt ends with slightly rounded outside portions as is shown in Fig. 6. When they burn with square ends as shown in this figure the breaks are very much more infrequent than with those shown in Fig. 4. Since the outside portions of the electrodes are rounded off as shown in Figs. 6 and 7 the condensed slag will less frequently cut out the lamps as is clearly shown in Fig. 7.

Referring to Fig. 2 the current enters the connection 11 and flows to an upper ring 25, where it divides, substantially half of the current going down through the conductor 26 and one-fourth flowing through each half of the ring 25 in opposite directions around the upper electrode. The current going down through the conductor 26 divides, substantially half flowing in opposite directions around the lower electrode through the halves of the ring 27 to the point 28. Here the current going down through the conductor 29 unites at the point 28 with the current flowing through the ring 27 and flows on out through the conductor 30 to the connection 12.

The conductors 5, 26, 29, and 30 are shown as being in the same plane in Fig. 2, however, it is not essential that they be thus placed. It is desirable, however, that the conductors 26 and 29 be in the same plane with the arc and spaced equal distances therefrom, and that the conductors 5 and 30 be in the same plane with the arc, and at equal distances therefrom. It will be understood that the length of the conductors 26 and 29 in this case may be adjusted to adjust the resistance in the two circuits as in Fig. 1. This adjustment would admit the balancing being maintained even if the two conductors were unequally spaced from the arc, as more current could be caused to flow through the conductor farthest from the arc. In this modification the current in support 5 balances the current in conductor 30, while the current in conductor 26 balances the current in conductor 29. This modification thus secures the beneficial results described in regard to Fig. 1.

In Fig. 3 the current flows as in the previous figures to the point 31. Here the current divides into substantially equal parts, approximately half flowing down through conductor 26 to the ring 27. Here the cur-

rent divides into substantially equal parts and flows in opposite directions around the electrode 2 through the ring to the point 28 and up through to the connection 32 to the point 33. Here it is joined by the other part of the current leaving the point 31, which flowed in substantially equal parts in opposite directions around the electrode 1 through the upper ring 25. The resistance 34 diagrammatically represents that the resistance of the connections between the points 31 and 33 is made adjustable to obtain the proper balancing as will be explained later. In this modification the whole current passing upward through the support 5 is partially balanced by the half of the current flowing down through the conductor 26. The net result will be that there will be a tendency to blow the arc toward the right in the figure by substantially half of the current. Since substantially half of the current flows upward through the conductor 32, there will be a tendency to blow the arc toward the left by this half of the current. The currents on opposite sides of the lamp therefore balance and the arc is free to burn on all parts of the carbon as in the other cases. In this modification the support 5, conductor 26, the electric arc and the conductor 32 should be in substantially the same plane, the conductor 26 and supports 5 on the one hand and conductor 32 on the other are on opposite sides of the arc and substantially equidistant therefrom. It is however, impossible to space the conductor 26 and the support 5 at exactly equal distances from the electric arc, it will be necessary to adjust the resistance 34 so that more than half of the current will flow down through the conductor 26 in order to produce exact balance. It will be understood that these adjustments may be obtained by merely varying the length and size of the connection between the points 31 and 33.

In Figs. 2 and 3 it is not necessary to use the rings 25 and 27, a single conductor, passing around one side of the electrode only, could be substituted for each ring. The lamp would balance in the same way if this were done.

In all three modifications disclosed, it is not essential that the arc be maintained stationary in order to obtain proper balancing. From an inspection of the circuits in the figures it will be apparent that the arc can travel up or down without destroying the balance.

A further result of my invention is that there is less obstruction to the light radiating outward in a horizontal plane. There are also no moving contacts and flexible leads exposed to the direct heat of the arc to be damaged thereby.

For the purpose of description of the operation of the lamps, it has been assumed

that the current used was a direct current with the positive terminal connected to the connection 11. However, alternating current can be used and equal balancing will be obtained as in the case where direct current is used, as will be evident to one skilled in the art.

Having described my invention what I claim is:

- 10 1. In an electric arc lamp, the combination of upper and lower electrodes, a plurality of conductors extending parallel to the electrodes, the lower end of one only being connected to the lower electrode,
- 15 means for connecting together the lower ends of two of said conductors and means for connecting together the upper ends of three of said conductors.
- 20 2. In an electric arc lamp, the combination of upper and lower electrodes, three conductors extending parallel to the electrodes and spaced therefrom, the lower end of one only being connected to the lower electrode, means for connecting together the lower ends of the other two of said conductors and means for connecting together the upper ends of said conductors.
- 25

3. In an electric arc lamp, the combination of upper and lower electrodes, a pair of conductors spaced from and extending parallel to said electrodes, the lower end of one only being connected to the lower electrode, a second pair of conductors also extending parallel to the electrodes and spaced therefrom, means for connecting the upper ends of said second pair together and to the upper end of one of said first pair of conductors, and means for connecting together the lower ends of said second pair of conductors.

4. In electric lamps, upper and lower electrodes, a conducting ring around the electrodes above the arc, a second conducting ring around the electrodes below the arc, means for connecting together the said rings on opposite sides of the arc, and a conductor for connecting the upper ring to the lower electrode.

In testimony whereof I have hereunto signed my name.

RICHARD B. CHILLAS, JR.
